UNITED STATES PATENT OFFICE.

GEORGE N. SPENCER, OF JACKSON, MICHIGAN.

MAGAZINE FIRE-ARM.

SPECIFICATION forming part of Letters Patent No. 310,328, dated January 6, 1885.

Application filed June 9, 1884. (No model.)

To all whom it may concern:

Be it known that I, GEORGE N. SPENCER, a citizen of the United States, residing at Jackson, county of Jackson, State of Michigan, 5 have invented a new and useful Improvement in Magazine Fire-Arms, of which the following is a specification.

The object of my invention is to effect certain improvements in this class of fire-arms, 10 to facilitate the operation.

The principal improvements pertain to the magazine and the mechanism for handling the cartridges.

In the drawings forming a part of this specification, Figure 1 is a broken side elevation of the arm, with portions removed, showing the internal construction; Fig. 2, the same with a change in the position of parts illustrating the operation. Fig. 3 is a cross-section 15 of Fig. 1 on line 1 1, with portions left full; Fig. 4, a broken section on line 2 2 in Fig. 2; Fig. 5, a detail enlarged in perspective; Fig. 6, a broken elevation of the arm, showing the side opposite to that in Figs. 1 and 2, with 20 side inclosure of the magazine removed; Figs. 7 and 10, details in enlarged perspective; Fig. 8, broken portion of the magazine enlarged; Fig. 9, rear end view of magazine with portions broken away; Fig. 11, a broken horizontal section of the breech and a top view of 25 the magazine.

The barrel and stock are shown connected with the breech by the illustrations A B, which parts may be of any suitable form applicable 30 to such fire-arms.

With the extension F of the breech-frame, which supports the barrel A, is connected a hand-plate, P, in a manner to slide forward and back, Fig. 6. With this hand-plate is 35 connected on one side of the fire-arm, Fig. 1, an operating-bar, m, having certain peculiar features, hereinafter described. On the outer side of the fire-arm, Fig. 6, is connected with said hand-plate a bar, e, which bar operates 40 the mechanism which controls the cartridge-supply. This hand-plate P is provided with a lock-trigger, D', the hooked end of which is adapted to catch in gains of the groove g, as 45 in Fig. 1, to hold the lock-plate and its connecting parts from contingent accidental displacement.

In the internal chamber of the breech, Fig. 4, is located a cartridge-carriage, a. This carriage is semi-tubular in form, the open side being to receive the cartridges c. The carriage 55 is supported by curved straps f, f, loosely located through loops o i, Fig. 10, said straps being secured at one end to a vertically-sliding plate, J, located at the side of the breech-chamber, Figs. 3, 4. By this means the carriage may be carried up and down in the breech-chamber and rotated in its circular supports f, f, to both receive a cartridge, c, 60 Fig. 3, and to clear the breech-block C when the latter is carried forward. One side, a", is 65 extended and thrown out of the line of the curve, to conflict with the cartridge-shell c" during the upward movement of the carriage, tossing it out, as at c", Figs. 2 and 4.

The sliding plate J is provided with a slot, 70 n, as shown by dotted lines in Fig. 10, in which slot the elbowed end of the pivoted L-lever d is loosely located. Said elbowed end plays in a slot through the wall E of the breech-chamber, Figs. 1, 2, 4, when carrying 75 the cartridge-carriage a up into the upper part of the breech-chamber. The lever d is provided with a tension-spring, z, and is thrown up in its action to raise the cartridge-carriage a by a shoulder on the under side of 80 the operating-bar m coming in contact with it during the backward movement of said bar, as shown in Fig. 2. The breech-block C is thrown backward by contact with a shoulder on the upper side of said bar during said 85 movement, as in Fig. 2. The breech-block is provided with the usual discharging-needle, of which no description is here needed. The fire-arm is provided with the usual hammer, Y, and trigger T, as well. The operating-bar 90 m has a pivoted lever, r, which conflicts with the breech-block during the forward movement of the operating-bar m, carrying said breech-block forward. As the bar m continues to move forward after the breech-block is in 95 place, the lever r rises up in a recess in the breech, as in Fig. 1.

H is a pivoted spring-actuated block for locking the breech-block C against a rebound when firing, the forward end of said block, 100 when in the position shown in Fig. 1, being located in a recess in the under side of the

breech-block C. (Not here shown.) The block H has a laterally-extended pin which enters the hook end B' of the bar m. The sides of this hook are angled diagonally to the line of bar m, by which means, when the bar m is carried forward the block H is thrown up in the recess in the breech-block above referred to. A rearwardly-extended lever, S', is connected with the pivoted block H, the rear end of which lever operates and holds the spring-actuated lock device e', Figs. 1 and 2. Thus when the bar m is carried forward, throwing up the forward end of the pivoted block H, the end of lever S' throws the lock device e' back, unlocking the trigger T, as in Fig. 1. In Fig. 2 the trigger is shown locked to prevent its being accidentally pulled previous to firing. One side of the breech-chamber has an opening for the admission of the cartridges c into said chamber from the magazine D. This opening may be closed with a door, L, hinged to the breech-chamber wall, Figs. 3, 4. The magazine shown at D has an incline bottom to allow the cartridges c to roll out of a door at the lower end of the wall of the magazine opposite to the door leading into the breech-chamber. When the magazine is not connected with the gun, this door may be closed by slide h', or by any suitable means. The magazine is provided with a lug on each end, one of which is caught in a niche in the wall E of the breech, Fig. 11, and the other is caught in a hook, w, of the spring-actuated bar e''. This bar e'' is located between the wall E and the magazine D in a groove in said wall, Figs. 6, 11. This arrangement holds the magazine connected with the breech in proper place. The magazine may be provided with one or more compartments of a proper width to hold a tier of cartridges, c, one piled above another. In Figs. 3 and 4 two compartments are shown, the wall u between them having a hinged door, n', at the bottom leading from one of the compartments into the other. This door n' is held closed by a pivoted lever, t, actuated by a spring, t', and held by the first tier of cartridges, Figs. 3, 8. When the cartridges of the first tier have all been used, the upper end of lever t is forced inward by the spring t', as in dotted lines in Fig. 8, and the cartridges, by the force of gravity behind the door, force it open and roll into the breech-chamber. The hooked end of bar e' carries a rod, z', which is located through a curved slot in the breech-wall below the magazine, Fig. 6. With one end of said rod, on the outside of the wall, is connected a pivoted V-lever, a', adapted to be thrown up in the passage-way of the cartridges c, Figs. 3 and 6, when the hand-plate P is carried forward, thus preventing further movement of said cartridge out of the magazine until proper time. With the other end of rod z' is connected a lever, b, which is adapted to be swung down at the same time lever a' is swung up, Fig. 3, and vice versa, as in Fig. 4. The upper end of the lever b is provided with a hook which en-

gages the edge of the carriage a during the downward movement of said lever b, which action revolves the carriage, bringing its open side in position to receive the cartridge set free by the removal of the lever b from the upright position seen in Fig. 4.

Any well-known mechanism may be used for drawing the cartridge-shell out of the barrel after firing. None is here shown. The shell is thrown out as the carriage a goes up, and the upper side of said carriage, coming in contact with the shell, throws it out of the breech-chamber, Figs. 4 and 2. When the breech-block C is carried forward, it forces the cartridge into the barrel A, as in other firearms. During said movement of the breech-block the lower side thereof conflicts with the edge a'' and slanting corner x of the carriage a, revolving said carriage to the position shown by dotted lines in the upper part of the breech-chamber in Fig. 3, and also forces said carriage down to its lower position in the chamber, where it receives a cartridge, c. It is at this time that the hooked end of lever b performs its function of revolving the carriage to receive a cartridge, above referred to.

The magazine may be provided with an indicator-hand or pointer, S, connecting with the swinging door n, Fig. 9, to show when the first compartment is empty, which fact is indicated when the hand is in the dotted position in said figure, the door n being then open.

Having thus described my invention, what I claim as new is—

1. A fire-arm provided with a vertically-playing cartridge-carriage having an open side to receive the cartridges, and adapted to rotate in its supports, a sliding breech-block, means for operating said carriage and breech-block, and a magazine adapted for the passage of cartridges therefrom into said carriage by the force of gravity, all substantially as set forth.

2. The combination, with a fire-arm and a substantially semi-tubular vertically-movable cartridge-carriage adapted to rotate in its supports, means for operating said carriage, a movable breech-block, and means for operating said breech-block, of a magazine adapted for the passage of cartridges therefrom by the force of gravity, substantially as set forth.

3. In a fire-arm, a magazine having compartments, the separating-partition of which is provided with a hinged door, in combination with a tilting lever, which, when held in position by the front tier of cartridges, holds said door closed, and when said tier of cartridges is removed tilts, releasing the door, whereby the latter may be forced open by the pressure of cartridges in the rear thereof, substantially as set forth.

4. A fire-arm having a breech-chamber and sliding breech-block, a substantially semi-tubular cartridge-carriage adapted to rotate in its bearings and to play vertically, a magazine adapted for the passage of cartridges there-

from into said carriage, alternately-operating levers in the cartridge-passage to control the cartridge-supply, a pivoted lever for operating said supply-levers, a sliding hand-plate, and connecting sliding bars for operating both the pivoted lever and breech-block, substantially as set forth.

5. The combination of a fire-arm, a magazine adapted for the passage of cartridges therefrom into the breech-chamber, levers in the cartridge-passage for controlling the cartridge-supply, a pivoted lever for operating the supply-levers, a sliding hand-plate, a sliding bar connecting the hand-plate for operating said pivoted lever, a vertically-playing cartridge-carriage, levers for supporting the carriage in an operative manner, a sliding breech-block, a pivoted spring-actuated breech-locking block, and a sliding operating-bar connecting with the hand-plate and adapted to operate the breech-block, the carriage-supporting levers, and the breech-locking block, all substantially as set forth.

6. In a fire-arm, the combination of a sliding breech-block, a trigger, a spring-actuated

trigger-lock, a pivoted lever for both operating and holding the trigger-lock and for locking the breech-block against a rebound, and a sliding hand-plate and connecting-bar for operating the pivoted lever and sliding breech-block, substantially as set forth.

7. In a fire-arm, the combination of a breech-chamber having a recess in the upper forward portion, a sliding breech-block, a sliding hand-plate, and an operating-bar connected to said hand-plate and provided with a pivoted lever, which engages the breech-block during the forward movement of the operating-bar, carrying said breech-block forward to place, and after said action enters the chamber-recess, whereby the operating-bar may be carried on forward, substantially as set forth.

In testimony of the foregoing I have hereunto subscribed my name in the presence of two witnesses.

GEORGE N. SPENCER.
